US0D1069278S

(12) **United States Design Patent** (10) **Patent No.:** **US D1,069,278 S**
(45) **Date of Patent:** **** Apr. 1, 2025**

(54) **CAT LITTER BOX**

(71) Applicant: **Xiaocong Huang**, Jieyang (CN)

(72) Inventor: **Xiaocong Huang**, Jieyang (CN)

(**) Term: **15 Years**

(21) Appl. No.: **29/964,780**

(22) Filed: **Sep. 25, 2024**

(30) **Foreign Application Priority Data**

May 7, 2024 (CN) 202430264406.5

(51) **LOC (15) Cl.** **30-11**

(52) **U.S. Cl.**

USPC **D30/161**

(58) **Field of Classification Search**

USPC D30/161

CPC A01K 1/0107; A01K 1/0111; A01K 1/0114;
A01K 1/0117
